UNITED STATES PATENT OFFICE.

DANIEL D. HUYETT, OF WILMINGTON, DELAWARE, ASSIGNOR TO ATLAS POWDER COMPANY, OF WILMINGTON, DELAWARE, A CORPORATION OF DELAWARE.

MEANS FOR INSURING UNIFORM PRESSURE UPON EXPLOSIVE CHARGES OF DETONATORS.

Application filed June 23, 1925. Serial No. 39,094.

To all whom it may concern:

Be it known that DANIEL D. HUYETT, a citizen of the United States, residing at Wilmington, in the county of New Castle and 5 State of Delaware, has invented certain new and useful Improvements in Means for Insuring Uniform Pressure upon Explosive Charges of Detonators, of which the following is a specification.

10 This invention relates to means for insuring uniform pressure upon the explosive charges of detonators.

In the manufacture of detonators it is 15 customary to deposit the explosive charge used, into a large number of detonator shells or metal casings, in a single operation, and then remove the rack containing the charged shells to a press where pressure is applied simultaneously to all of the charges by 20 means of numerous metal punches, one of which enters the open end of each shell. These punches are mounted in a common press head and, with equal length punches, 25 all charges are thus compressed to a uniform height.

It is a well known fact that by any of the 30 methods which may be employed commercially, an exactly uniform weight of charge cannot be deposited into the detonator shells. This is due to the fact that the charges are 35 measured out by first filling a series of holes of the approximate cubical content desired, with the explosive used and then permitting this charge to fall into the shells. Variations in density of the explosive as well as 40 variations in its flowing properties render it impossible to deliver charges of exactly uniform weight. As a consequence, with the usual methods of pressing, the under-weight charges are under-pressed while the over-weight charges are over-pressed.

The over-pressed charges may result in 45 distorted and bulged detonator shells and there is also the possibility of rendering the charge non-explosive by over-compressing, as for example, "dead-pressed" fulminate charges. On the other hand, underpressed charges are conducive to even greater 50 ills. The explosive charge, not being firmly pressed into a common mass, tends to loosen and subsequently fall out of the open end of

the detonator shell. The presence of loose explosives in the metal containers, in which detonators are usually packed, constitutes a 55 hazard in itself. Furthermore the possibility of detonators, from which part or all of the explosive charge has been lost, being used for setting off other explosives, may result in the well known dangerous and 60 costly misfires.

The use of hydraulic pressure to equalize the thrust exerted by the 202 press points, mounted on the head of a fulminate seating press, presents many advantages. The one great draw back in the use of this method 65 arises from leakage of the oil, water or other pressure medium, past the pistons and onto the press points where it comes in contact with and desensitizes the fulminate. 70

Therefore, one of the primary objects in the present invention is to provide a hydraulic equalizing structure, of the character indicated, by means of which uniform 75 pressure may be exerted upon the explosive charges while at the same time leakage of the pressure medium, to and upon the punches, will be effectively prevented.

In my copending application, Serial Number 39,093, filed June 23, 1925, there is disclosed a structure designed to avoid the above named difficulties, wherein a plurality of pistons are subjected to a uniform hydraulic pressure, said pistons in turn transmitting this pressure to the several press 80 85 punches.

In the present construction, each press point is acted upon by an expansible element 90 that is filled with a pressure fluid and which receives its pressure fluid supply from a source common to all of the expansible elements.

In the accompanying drawing, I have illustrated, partly in side elevation and partly 95 in vertical section, a portion of a press head constructed in accordance with the invention.

The press head comprises a cap plate 5, body portion 6 and a base plate 7. The 100 base plate is recessed, as indicated at 8, for the heads 9, of the press points or punches 10. Pressure is exerted upon each of the press points by an aligned, expansible ele-

ment in the nature of a metallic bellows 12; pressure fluid such as oil or water under pressure being admitted to said bellows. Since all of these bellows are alike in construction, a description of one will serve as a description of all. The lower end of the bellows is embedded in and made substantially integral with a block 13. A rod 14 projecting downwardly from the underside 5 of block 13 bears upon the head 9 of the press point. The upper end of the expandible element is embedded in and made substantially integral with a block 15, the upper end of which carries an outstanding 10 flange 16. A lead gasket 17 is compressed when a hollow packing nut 18 is screwed into place in body 6. The nut 18, which is a retaining nut, and the block 15, are provided with aligned openings, 19 and 20, respectively, through which the pressure fluid may find its way to the interior of the expandible element or bellows 12. The interior of the nut 18 is of angular shape so that, by the use of a socket wrench, this 15 nut may be screwed into place, to force the flange 16 tightly upon the gasket 17. A conduit 21 is formed in the cap 5 and is in communication with the interior of all of the nuts 18. Thus, if fluid under pressure 20 be admitted to the conduit 21, a uniform pressure will exist inside of all of the expandible elements 12, and consequently, the pressure exerted by the several press points or punches will be exactly the same. This 25 insures a uniform compression of the explosive charges in the detonators under the action of the several punches.

While I prefer the use of hydraulic pressure to secure uniformity in the compression 30 of the explosive charges, I may employ springs in the place of the expandible elements. In Fig. 2 I have illustrated a construction wherein a spring 25 bears upon the head 9 of the punch, to render said 35 punch yieldable. The tension of the spring may be adjusted by manipulation of a screw

26, said screw carrying a plate 27 at its lower end which bears upon the upper end of the spring.

It is to be understood that the invention 50 is not limited to the precise construction set forth but that it includes within its purview whatever changes fairly come within either the terms or the spirit of the appended claims. 55

Having described my invention, what I claim is:

1. A device of the character described comprising a plurality of press points, a plurality of elements having expandible 60 walls bearing upon said press points and means for admitting pressure fluid from a common source to the interior of all of said elements.

2. The combination with a movable press head, a plurality of press points, carried thereby, a plurality of elements having expandible walls mounted in alignment with said press points and comprising portions bearing upon said points, compression nuts 70 for securing said elements in place and means for admitting pressure fluid, from a common source, to all of said elements through said compression nuts.

3. The combination with a press head 75 carrying a plurality of press points of a metallic bellows mounted in alignment with each of said press points and comprising an element bearing on the press point, and means for admitting pressure fluid, from a 80 common source, to all of said bellows.

4. A structure as recited in claim 3, in combination with a packing means for each of said bellows, a hollow compression nut for compressing the bellows upon said packing means and means for conducting pressure fluid through said nuts to the interior of the bellows. 85

In testimony whereof he affixes his signature.

DANIEL D. HUYETT.
